HAT IRONING MACHINE

Karl Couyoumjian, Detroit, Mich.

Application July 11, 1933, Serial No. 679,943

5 Claims. (Cl. 223—28)

This invention relates to hat ironing machines and has for the primary object the provision of a machine of the above stated character which is equipped with power driven means for supporting hat forms or molds either of the type for cleaning the crown of a hat or the brim of the latter and associated with such means is an electric iron so supported that it may be manually manipulated to act on the crown and brim of the hat supported and rotated by said means and also supporting the operator's arm to relieve tiring strains thereon.

With these and other objects in view this invention consists in certain novel features of construction, combination and arrangement of parts to be hereinafter more fully described and claimed.

For a complete understanding of my invention, reference is to be had to the following description and accompanying drawings, in which

In the drawings:

Figure 1 is a fragmentary vertical sectional view illustrating a hat ironing machine constructed in accordance with my invention.

Figure 2 is a top plan view illustrating the same.

Figure 3 is a sectional view taken on the line 3—3 of Figure 2.

Figure 4 is a detail sectional view illustrating a support for the iron when at rest.

Figure 5 is a detail view illustrating the pivotal connection between the iron and its arm or lever.

Figure 6 is a detail view partly in section illustrating the mounting of the arm or lever of the iron to a support.

Referring in detail to the drawings, the numeral 1 indicates a main support which may be of any desired construction and preferably of a type to house or enclose an electric motor 2, the latter being mounted in a bracket 3 carried by the support 1. A shaft 4 is journaled to the support 1 and rises vertically from the top face of said support and is connected to speed reducing gears 5 driven from the motor by an endless belt 6. Secured to the shaft 4 above the support 1 is a hat mold supporting element 7 including upper and lower plates 8 and 9 integrally connected. The plate 9 is of substantially oblong shape while the plate 8 is of substantially circular shape. Rising from the plates 8 and 9 are pins 10 to be received in sockets 8' formed in hat forms 11 and 12. The form 11 is of the type employed to support the crown of a hat while being worked upon while the form 12 is of the type to support the brim of the hat to be worked upon. It is to be understood that when the hat is being treated or

ironed only one form is in use. The hat thus supported is rotated by the motor 2, the latter being controlled by a suitable switch 13 carried by the support 1.

Rising from the support 1 laterally of the form supporting element 7 is a standard 14 carrying a bracket 15. The bracket 15 is connected to the standard 14 by a set screw 16 whereby the bracket may be rotated about the standard 14 when desired. A rod 17 is slidably mounted to the bracket 15 and is disposed horizontally and carries a forked portion 18 provided with oppositely arranged pivots 19 which pivotally connect a sleeve 20 to the rod 17. A hollow lever 21 is slidably mounted in the sleeve 20 and one end of the lever is flanged, as shown at 22, to prevent said lever from being pulled out of the sleeve, the sleeve normally occupying a position adjacent the flanged end 22 of the lever. A hand grip 23 is mounted on the lever intermediate the ends of the latter and the free end of the lever carries a head 24 to which is pivoted an electric iron 25. The lever may be moved towards and from the standard 14 and also swung relative to the latter on the pivots 19. Besides said lever 21 may be rotated within the sleeve 20. These described connections permit manual manipulation of the lever so that the iron may be brought into contact with all faces or surfaces of a hat supported by either of the forms 11 or 12, it being understood that the operator grasps the hand grip 23 for the manipulation of the iron. Spaced arm rests 26 and 27 are carried by the bracket 15. The operator when manipulating the lever 21 may rest his arm upon either of the arm rests. The arm rest 26 is smaller than the arm rest 27 so that a person may place the arm on the rest 27 without being interfered with by the rest 26. Electrical conductors 28 for the electric iron preferably extend through the hollow lever 21 and into the support 1 and an insulating sleeve 21' is mounted in the handle about the conductors 28. The circuit to the iron is controlled by a switch 29 and also in said circuit is positioned a current regulator 30 for the purpose of controlling the temperature of the iron. If desired, a thermostatic control for the iron may be built on to the latter and in the electric circuit.

A standard 31 rises from the support 1 laterally of the standard 14 and carries a forked portion 32 to provide a seat for the free end of the lever 21 when said lever and iron are not in use.

While I have shown and described the preferred embodiment of my invention, it will be

understood that minor changes in construction, combination and arrangement of parts may be made without departing from the spirit and scope of my invention, as claimed:

- 5 5 Having described the invention, I claim:
  1. A hat ironing machine comprising a main support, power driven means for rotatably supporting hat forms to the main support, a standard rising from the main support, a bracket rotatably secured to the standard, a rod slidably secured to the bracket and extending horizontally therefrom over the main support, a hollow lever pivotally and slidably connected adjacent one end to said rod, a hand grip for said lever, and an electric iron pivoted to the other end of the lever.
  - 10 10 2. A hat ironing machine comprising a main support, power driven means for rotatably supporting hat forms to the main support, a standard rising from the main support, a bracket rotatably secured to the standard, a rod slidably secured to the bracket and extending horizontally therefrom over the main support, a hollow lever pivotally and slidably connected adjacent one end to said rod, a hand grip for said lever, and an electric iron pivoted to the other end of the lever, means on the main support for supporting the last-named end of the lever when not in use.
  - 15 15 3. A hat ironing machine comprising a main support, power driven means for rotatably supporting hat forms to the main support, a standard rising from the main support, a bracket rotatably secured to the standard, a rod slidably secured to the bracket and extending horizontally therefrom over the main support, a hollow lever pivotally and slidably connected adjacent one end to said rod, a hand grip for said lever, an electric iron pivoted to the other end of the lever, means on the main support for supporting the last-named end of the lever when not in use.
  - 20 20 30 30 35 35 3. A hat ironing machine comprising a main support, power driven means for rotatably supporting hat forms to the main support, a standard rising from the main support, a bracket rotatably secured to the standard, a rod slidably secured to the bracket and extending horizontally therefrom over the main support, a hollow lever pivotally and slidably connected adjacent one

end to said rod, a hand grip for said lever, an electric iron pivoted to the other end of the lever, means on the main support for supporting the last-named end of the lever when not in use, and arm rests carried by the bracket and arranged in different planes to each other on which the operator of the lever may rest his arms.

4. A hat ironing machine comprising a main support, means for movably supporting an iron to the main support, a shaft journaled to the main support, electrical power means for rotating the shaft, upper and lower form plates integrally connected with each other and secured to said shaft, and pins carried by said plates to fit in sockets of hat brim and hat crown forms, said upper form plate being smaller than the lower form plate to permit a hat brim form to pass the upper form plate and rest on the lower form plate with the upper form plate therein.

5. A hat ironing machine comprising a main support, means for movably supporting an iron to the main support, a shaft journaled to the main support, electrical power means for rotating the shaft, upper and lower form plates integrally connected with each other and secured to said shaft, pins carried by said plates to fit in sockets of hat forms, said upper form plate being of a different shape and smaller in size than the lower form plate, said lower form plate adapted to support a hat brim form with the upper form plate therein and the upper form plate adapted to support a hat crown form spaced from the lower form plate to prevent a hat positioned thereon from contacting with said lower form plate.

KARL COYOUUMJIAN.
